DESCRIPTION

U.S. PATENT DOCUMENTS

FIG. 1 is a front view of an image of a display screen or portion thereof with graphical user interface according to a first embodiment thereof; and,

D525,632 S 7/2006 Jost et al.
D554,652 S * 11/2007 Shen D14/485
D599,807 S 9/2009 Marashi
D599,815 S 9/2009 Ogura et al.
D602,948 S 10/2009 Ogura et al.
D612,860 S * 3/2010 Tarara D14/485
D625,317 S 10/2010 Jewitt et al.
D626,132 S * 10/2010 McLaughlin D14/485
8,040,253 B2 * 10/2011 Kaller B60Q 9/008

FIG. 2 is a front view of an image of a display screen or portion thereof with graphical user interface according to a second embodiment thereof.

The broken line showings of portions of a display screen, text, and other features in the figures are environmental only and form no part of the claimed design.
